(57) **CLAIM**

The ornamental design for a display package, as shown and described.

DESCRIPTION

FIG. 1 is a front-left perspective view of the new, original, and ornamental design for a display package, showing a product in phantom lines retained on the display package;

FIG. 2 is a front-right perspective view of the display package of FIG. 1, showing a product in phantom lines retained on the display package;

FIG. 3 is a front-left perspective view of the display package of FIG. 1;

FIG. 4 is a front-right perspective view of the display package of FIG. 1;

FIG. 5 is a left side view of the display package of FIG. 1;

FIG. 6 is a top view of the display package of FIG. 1;

FIG. 7 is a front view of the display package of FIG. 1;

FIG. 8 is a right side view of the display package of FIG. 1;

FIG. 9 is a bottom view of the display package of FIG. 1; and,

FIG. 10 is a rear view of the display package of FIG. 1.

The portions of the FIGS. 3, 4, 7 and 10 shown in phantom lines form no part of the claimed design. The phantom lines in FIGS. 1 and 2 illustrate environmental structure that forms no part of the claimed design.
